ASSIGNORS TO OXWELD RAILROAD SERVICE COMPANY, A CORPORATION OF DELA-
WARE

COMBINATION TIE PLATE

Application filed November 27, 1929. Serial No. 410,234.

The present invention pertains to a combination tie plate for attaching a railroad rail to a concrete tie or a concrete roadbed, and it has for its main object that of providing such a tie plate which employs no spikes or similar devices and consequently no spike receiving means such as wood block inserts set in the concrete tie or roadbed. Such inserts are unsatisfactory on account of their comparatively short life. The spikes that are used with them are also unsatisfactory on account of their insecure grip on the rail which results in the need for anti-creepers that are themselves only partially satisfactory. Therefore, another object of this invention is to provide a combination tie plate that will hold a rail with sufficient firmness to prevent it from creeping thereby eliminating all need for anti-creepers. Another object is to provide a combination tie plate that may be fastened to a concrete tie either when it is cast or when it is placed in service, and when so fastened provides means for automatically spacing the rails one from the other thereby eliminating all need for making this measurement when the rails are laid. Another object is to provide a tie plate that when injured may be detached from either a concrete tie or concrete roadbed and replaced. Other objects and novel features will be apparent from the following description and the accompanying illustration in which:

Fig. 1 is a side view of our improved combination tie plate attached to a rail;
Fig. 2 is an end view of the same as used to join a rail to a concrete tie;
Fig. 3 is an end view of the same as used to join a rail to a concrete roadbed;
Fig. 4 is a top view of the same with a rail attached thereto;
Fig. 5 is a perspective of the clip forming part of our improved combination tie plate;
Fig. 6 is a perspective of the wedge forming part of the same;
Fig. 7 is a perspective of the key forming part of the same;
Fig. 8 is a side view of the cotter forming part of the same;
Fig. 9 is a side view of the wedge plate used

to secure our combination tie plate to a concrete roadbed.

Our improved combination tie plate may be constructed in various ways but the preferred form shown in the accompanying drawing comprises a tie plate 10, a clip 14, a wedge 17, a key 19, a cotter 21, and a wedge plate 22 of which two are used for the purpose of securing the tie plate 10 to a concrete roadbed.

The tie plate 10 is preferably made of a sheet of steel of suitable size which is bent into the form shown having a flat top 30 substantially the width of the concrete tie with which it is to be used and depending sides 29 extending down the sides of the tie with the lower edges thereof turned inward as shown at 24 so they rest against the under side of the tie. One or more openings or slots 28 are provided in the depending sides 29 through which bolts 31 are inserted to secure the tie plate 10 to a concrete tie such as that shown at 32. Suitable openings for the bolts 31 may be provided in the tie 32 by any approved method such as inserting pieces of pipe 33 in the tie when it is cast or formed. In some cases the inturned edges 24 may be dispensed with when service conditions are light, or a larger number of the bolts 31 may be used when service conditions are especially severe.

From one end of the top 30 of the tie plate 10 a tongue is separated and turned upward to form a socket 11 for one edge of the base of the rail 13. The sides of the socket 11 may be separated from the tie plate 10 by a saw cut or the socket may be sheared and pressed out in a die. When complete it should fit the base of the rail snugly to prevent the rail from moving with respect to the tie plate. At the other end of the tie plate 10, and in alignment with the socket 11, another tongue is separated and bent upward and over to form an abutment 12 for a wedge 17 to be described later. This abutment should extend upward the height of the wedge and then over thereby forming a recess for the wedge.

Extending through the top 30 of the tie plate 10 is an opening 34 in linear alignment

with the socket 11 and the abutment 12 and positioned so the outer edge thereof is substantially in vertical alignment with the inner edge of the rail 13 when the outer edge thereof is seated in the socket 11. The width of the opening 34 is substantially that of the socket 11 and the abutment 12 and the length thereof is sufficient to allow the clip 14 to pass therethrough.

10 The clip 14 is a rectangular block of steel having a recess 15 in the outer face with the walls thereof inclined with respect to each other and positioned so they clamp the inner edge of the base of the rail 13 to the outer edge of the opening 34 when the walls of the recess are forced over the contiguous edges thereof. The inner face of the clip 14 has a recess 16 therein adapted to receive the outer face of the wedge 17. The width of the clip 14 is slightly less than that of the opening 34 so the clip will move freely in the opening without undue lateral motion.

15 The wedge 17 is a rectangular block of steel having angular sides and an aperture 25 through the small end thereof. One side of the wedge is adapted to fit in the abutment 12 and the other side is adapted to fit in the recess 16 in the clip 14. The aperture in the wedge is for the purpose of receiving the key 19.

20 The key 19 has tapering sides and a thickness adapted to permit it to pass through the opening 18 in the wedge. In the small end thereof a plurality of holes 20 are provided for the purpose of receiving a cotter such as that shown at 21 for the purpose of holding the key in fixed position with respect to the wedge when the device is assembled.

25 The wedge plate 22 is a rectangular piece of sheet metal having a plurality of notches 23 in each edge thereof for the purpose of withdrawing it from the opening in a concrete roadbed where it is used to lock the tie plate in place in a manner to be described later.

30 The construction of our combination tie plate and its method of operation are clearly shown by the assembled views thereof. The rail 13 is attached to the tie plate 10 by seating one edge of the base of the rail in the socket 11 as shown in Figs. 1 and 4. The clip 14 is inserted in the opening 34 and then moved so the walls of the recess 15 surround the contiguous edges of the rail and the opening 34. The wedge 17 is inserted between the clip 14 and the abutment 12 which is set at an angle to the clip so the outer edge of the abutment and the recess 16 in the inner edge of the clip will bear squarely against the sides of the wedge. The key 19 is then inserted in the aperture 18 in the wedge 17 with the small end of the key toward the rail 13. In this position one edge of the key bears against the wall of the aperture 18 and the other edge bears against the side of

the clip 14 and the side of the abutment 12. In order to clamp the parts together and lock the rail to the tie plate, the key 19 is driven into the aperture 18 in the wedge 17 thereby moving it so its wedging action moves the clip 14 and causes the angular walls of the recess 15 to clamp the rail 13 to the tie plate 10 with sufficient pressure to prevent the rail from moving with respect to the tie plate when in service. When the parts are securely locked together a cotter 21 is inserted in the one of the holes 20 that is nearest the side of the wedge 17 facing the rail 13. This cotter holds the parts of the combination tie plate together and prevents them from becoming loosened by the vibration of passing trains.

35 When the combination tie plate is used with a concrete tie the plate 10 is formed so it closely fits the outside of the tie, suitable openings are provided in the tie in alignment with the openings 28 in the tie plate, and the plate is secured to the tie by suitable bolts such as that shown at 31. As previously mentioned, the inturned edges of the depending sides 29 may be left off and the sides of the tie plate terminated just below the bolt holes 28.

40 When the tie plate is used with a concrete roadbed such as that shown in Fig. 3, suitable openings in the roadbed are provided for the depending sides of the tie plate. Two openings are provided for each tie plate. They are substantially the length of the tie plate and they are arranged side by side so the inner walls are the same distance apart as the inner walls of the sides 29. Each opening is as wide as the combined thickness of one of the sides 29 of the tie plate and one of the wedge plates 22. At the bottom of each opening there is a recess 27 extending inwardly which is of suitable size to receive one of the inturned ends 24 of one side of the tie plate. Metal reenforcing bars or plates 25 may be provided in the foundation so they form the upper wall of the recesses 27 and provide a hard surface for the inturned ends 24 to lock in under.

45 When a tie plate is attached to a concrete foundation provided with suitable openings, the depending sides 29 of the tie plate are forced apart just far enough to permit the inturned ends 24 to enter the openings. The tie plate is then lowered until it rests against the upper surface of the foundation. When in this position one of the wedge plates 22 is forced in one of the openings in the foundation outside of the depending side of the tie plate thereby forcing the inturned end 24 into the recess 27. Another wedge plate is then forced in the other opening alongside of the other depending side of the tie plate thereby forcing its inturned end into the recess provided therefor. Notches 23 are provided in the edges of the wedge plates 22 for the purpose of withdrawing them from the openings

in the foundation so the tie plate may be removed.

When forming either a concrete tie or a concrete foundation for use with our improved combination tie plate a recess should be provided under the opening 34 in the tie plate for the purpose of receiving the lower end of the clip 14 that extends below the tie plate for the purpose of clamping it to the rail.

Our tie plate may also be used with a wood tie and in that case the depending sides 29 need not extend down so far as when used with a concrete tie and the inturned ends of the sides may be left off entirely. The openings 28 in the sides may be located a little nearer the top of the plate, and ordinary railroad spikes may be driven through these openings to hold the tie plate to the tie. Preferably, the spikes should be driven near the bottom of the vertically elongated openings 28 so the downward movement of the tie plate caused by the passing of trains will not loosen the spikes. A recess for the bottom of the clip 14 may be provided in wood ties by boring a two inch hole three quarters of an inch deep in the proper location.

The tie plates 10 may be attached to both concrete and wood ties where they are made and then distributed along the right of way with the ties. The tie plates may be placed on the ties so each of the sockets 11 is at the outside of the rail, or they may be attached so one is outside and one is inside. By properly spacing the tie plates when they are attached to the ties the rails will be properly spaced when they are attached to the tie plates so all need for measuring the width of the tread when the rails are laid will be eliminated.

Various changes in the form and arrangement of the component parts may be made and other equivalent materials may be substituted for those mentioned without departing from the spirit of the invention or sacrificing any of the rights thereunder.

We claim:

1. Means for attaching a railroad rail to a concrete tie, comprising a plate having depending sides with the lower edges thereof turned inward; said plate being provided on the upper side thereof with a socket for said rail, an abutment at an angle thereto, and an opening therein between said socket and said abutment; a clip adapted for being moved to clamp said rail to the edge of said opening; a wedge adapted for being moved between said abutment and said clip to move the latter, said wedge being provided with an aperture therethrough; a tapered key in said aperture adapted for being moved between one wall of said aperture, on one side, and said clip and said abutment, on the other, to move said wedge, said key being provided with a plurality of holes therein; and a cotter in one of said holes to hold said key in

fixed position with respect to said wedge thereby locking said means together.

2. Means for attaching a railroad rail to a concrete tie, comprising a plate adapted for being attached to said tie and provided on the upper side thereof with a socket for said rail, an abutment, and an opening therein between said socket and said abutment; a clip within said opening adapted for being moved to clamp one edge thereof to said rail; a wedge positioned entirely above said plate and cooperating with said abutment to move said clip; a tapered key also above said plate for moving said wedge; and means for holding said key in fixed position with respect to said wedge.

3. Means for attaching a railroad rail to a concrete tie, comprising a plate adapted for being attached to said tie and provided with two portions thereof turned upward and over to form, respectively, a socket for said rail and an abutment at an angle to said socket for the rail clamping means; a clip having a recess therein with inclined walls adapted for clamping said rail to said plate; and means movable between said abutment and said clip to move the latter.

4. Means for attaching a railroad rail to a concrete tie, comprising a plate adapted for being attached to a tie and provided with an integral socket for said rail, an integral abutment having a recess, and an opening having one edge thereof substantially in alignment with one edge of said rail when the other edge of said rail is seated in said socket; a clip extending through said opening in said plate and provided on one side with a recess having inclined walls adapted for bearing upon the upper side of the base of said rail and upon the under side of said plate to clamp them together, and on the other with a recess adapted for receiving a wedge; a wedge having one side thereof in the recess in said abutment and the other side thereof in the recess in said clip; a key for moving said wedge; and means for holding said key in assembled position.

5. Means for attaching a railroad rail to a concrete tie, comprising a plate adapted for being attached to a tie and provided with a socket and an abutment; means for clamping said rail to said plate; a wedge for moving said means provided with an aperture in the small end thereof; a key in said aperture adapted for moving said wedge and provided with a hole in the small end thereof; and means in said hole for holding said key in fixed position with respect to said wedge.

6. Means for attaching a railroad rail to a concrete foundation comprising a plate having each edge thereof turned downward and adapted for extending into an opening in said foundation, and provided with a projection on the side thereof adapted for extending into a recess in the side of said open-

ing; means for holding said projection in said recess; and means for attaching said rail to said plate.

7. Means for attaching a railroad rail to a concrete foundation, comprising a plate having a plurality of portions each adapted for extending into an opening in said foundation, and provided with a projection on the inside thereof adapted for extending into a recess in the side of said opening; a wedge plate adapted for being driven into each opening to force said projection into said recess, and provided with notches therein for the removal thereof; and means for attaching said plate to said rail.

8. Means for attaching a railroad rail to a concrete foundation, comprising a plate having each edge thereof turned downward and adapted for extending into an opening in said foundation, the lower edge of each downturned portion being turned inward and adapted for extending into a recess in the side of its associated opening; a wedge plate adapted for being driven into each opening alongside the downturned edge of said plate to force the inturned edge thereof into said recess; and means for attaching said plate to said rail.

9. Means for attaching a railroad rail to a concrete foundation, comprising the combination of a plate having depending sides with the edges thereof turned inward and adapted for projecting into recesses in said support; means for holding said inturned edges into said recesses; a clip adapted for being moved to clamp said rail to said plate; a wedge adapted for moving said clip; a key adapted for moving said wedge; and means for holding said key in fixed position with respect to said wedge.

In testimony whereof, we affix our signatures.
